(57) **CLAIM**

I claim, the ornamental design for a digital A/V player, as shown and described.

DESCRIPTION

FIG. 1 is a top and front perspective view of a digital A/V player, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference view showing how the digital A/V player can be used by a user.

The broken lines shown in the figures are for illustrative purposes only and form no part of the claimed design.
